UNITED STATES PATENT OFFICE

JAMES B. JOHNSON, OF POPLAR, MINNESOTA

RURAL MAIL BOX

Application filed February 25, 1928. Serial No. 256,936.

The present invention relates to an improved mail box which is expressly designed for use in rural districts, the same being particularly adaptable for use where a group or 5 a multiplicity of mail boxes are supported in close proximity to each other, on a platform such as frequently seen in rural districts.

It is well known that under this arrangement of grouping mail boxes, many of the 10 recipients of the mail are great distances from the platform. This naturally promotes tampering, sometimes by curious people seeking information, and in many instances, resulting in loss of mail.

Having observed these disadvantages from 15 time to time, I have conceived of and evolved a box which is characterized in one instance by a key controlled lock in order to prevent unscrupulous persons from obtaining access 20 to the box unless provided with a key.

Another feature of the invention is a rotary slotted drum or cylinder constructed for receiving the mail and rotatably mounted to permit it to be turned and to drop the mail 25 into the box proper, whereby to conceal it from view.

And a further feature is a sectional hood composed of hingedly connected sections, hinged to the box and drum and constructed 30 to accommodate and cover the drum.

Other features and advantages of the invention will become more readily apparent from the following description and drawings.

In the drawings:—

Figure 1 is a view with portions broken away to disclose the internal details.

Fig. 2 is a transverse vertical section thru the improved mail box.

Fig. 3 is an enlarged fragmentary sectional view showing the hinge connection between the sectional hood and the drum.

In carrying out the invention, I provide a substantially rectangular box 4 in the upper end of which the rotary mail receiving cylinder or drum 5 is disposed. The drum is pivoted to the upper extended portion of the end walls of the box as indicated at 6.

This drum, which is of horizontal elongated form, is provided on one side with a relatively wide mail slot 7. In addition, it is

provided with an internal resilient clip 8 for outgoing mail. Then, on the front side it is provided with a longitudinally disposed hinge knuckle 10 for passage of a hinge pin or pintle 9. The pin passes through the part 55 10 and through a pair of lugs 8 on the front section 11 of a sectional hood or weather shield 12.

Incidentally, the hood embodies a similar section 13, these sections being of arcuate 60 form to accommodate the protruding upper half of the drum 5. The section 13 is hinged as at 14 to the rear wall of the box 4 and the two sections are hingedly connected together as at 15. The front section 11 is formed with an outstanding weather guard or flange 16 65 having an appropriate handle 17.

One end wall of the box is formed with a hinged door 18, equipped with an appropriate pad lock 19. This permits the lawful owner 70 to obtain access to the box.

On the front side of the box is a small coin receiver 20 having a coil slot 21 and a slide valve plate 22 in its bottom. This is to accommodate the change deposited by the mail man or by the owner of the box for the mail 75 man. In addition, it will accommodate stamps, permitting the stamps to be easily removed and obviating the necessity of searching for these in the bottom of the box 80 proper.

In practice, the device is fastened to an appropriate supporting member or post in any convenient manner. When the hood is raised (see dotted lines), the drum is rotated 85 through an appropriate half circle and the mail is deposited, whereupon the drum is turned over to occupy the position shown in Fig. 2, to conceal the mail that has been deposited.

The mail will drop into the box proper, and by unlocking the lock 19, and opening the door 18, access can be had to the interior of the box.

The advantages and features of an invention of this class will be clear to persons familiar with the art. Therefore, a more lengthy description is regarded unnecessary.

Minor changes in shape, size, and re-arrangement of parts coming within the field 100

of invention claimed may be resorted to if desired.

Having thus described my invention, what I claim as new is:—

5 In a mail box of the class described, a substantially rectangular opened top box provided at one end with an entrance opening, a hinged door for said entrance opening, locking means for said door, a horizontally disposed cylindrical drum rotatably mounted in the upper end portion of the box, said drum being provided with a relatively large opening on one side thereof, and said drum being adapted to receive mail for depositing the latter within said box, a hood for the open top of said box, said hood comprising a pair of hingedly connected sections of arcuate formation to correspond with the upper portion of the drum, one of said sections being hingedly connected to said box and the other of said sections being hinged to the drum for rotating the latter whereby said drum may be actuated upon the raising and lowering of said hood for receiving and discharging mail into said box.

23 In testimony whereof I affix my signature.
JAMES B. JOHNSON.
